UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed March 17, 1926. Serial No. 95,222.

This invention relates to sound-deadening casings for typewriting machines, and more particularly to means for feeding a continuous web to the platen of a typewriting machine enclosed in the casing.

In certain classes of work, such as, for instance, when typing telephone messages, it is customary to type the message rapidly, directly as it is being received over the telephone. In such cases, it is of importance that the machine be operated in a sound-deadening casing, otherwise the noise arising from the operation of the machine is liable to interfere with the clear reception of the message. The work requires the use of a roll or pack of paper web, which, according to the present invention, is inserted at the rear of the casing, and then passed around the enclosed platen, and thence out again to the exterior of the casing. The typed messages are torn off by a knife, which may be secured to the wall of the casing at the delivery side thereof. A difficulty arises owing to the relative movement between the carriage and the walls of the casing, since the web which is carried by the carriage drags along the walls of the casing.

One of the features of this invention relates to means for obviating this difficulty. To this end, it is proposed to slot the rear wall of the casing and to extend through the slot, to the exterior thereof, a pair of web-guiding and supporting plates carried by the carriage, and to pass both the incoming and outgoing portions of the work-sheet between said plates, thereby preventing the work-sheet from contacting with the sides of the slot.

Another feature relates to means for severing the typed forms or portions of the web into form length without necessitating the opening of the casing cover. According to this feature of the invention, the web is torn off, after typing, against a knife fast to the edge of the slot.

According to the method of handling the work in this invention, the web is passed over a rear table, which extends through the slot in the wall of the casing, and is guided down a chute at the rear of the platen, and is then inserted around the platen and over a front table, which extends also to the outside of the casing through the same slot through which the rear table protrudes. Over said front table

there is provided a guard which serves as a means for preventing contact between the typed forms and the upper side of the slot in the casing, which, for the purpose of preventing the leakage of sound-waves, 60 may be provided with slot-sealing devices fast to the edges of the slot. After typing each form, the platen is rotated by means of the line-space handle, and then the typed form is torn off against the knife at the 65 delivery side of the slot.

From the foregoing description of operation, it will be noted that the forms may be typed without necessitating the opening of the cover of the sound-deadening casing, 70 as has been the practice heretofore. However, the cover may be displaced when desired by just swinging it rearwardly in the regular way. It will also be noted that in order to further increase the efficiency of 75 the device, a shiftless machine is provided, which, as is well known, is much easier to operate at a high rate of speed, since the operative is not distracted by the case-shifting operation.

Other features and advantages will herein-after appear.

In the accompanying drawings,

Figure 1 is a cross-sectional view, in elevation, and shows the invention applied to an 85 Underwood typewriting machine in a sound-deadening casing.

Figure 2 is a similar view, showing the cover in its partly-open position.

Figure 3 is a cross-sectional view through 90 line 4—4 of Figure 1, and shows the carriage moved all the way to one end of the casing.

Figure 4 is a cross-sectional view through the line 5—5 of Figure 1, and shows the rear table and the slot-sealing devices.

The Underwood typewriting machine with which this invention is illustrated includes a frame 10 having a forward extension 11, for enclosing banks of keys 12, which keys, when operated, are effective to swing 100 type-bars 13, to strike a platen 14. Said platen is revolubly mounted on a platen-shaft 15, and may be rotated by means of finger-pieces 16, and also by means of a line-space lever 17. The platen is carried by a carriage-frame 18, which is mounted for letter-space travel along rails 19, carried by the frame 10.

In order to deaden the sound arising from the use of the machine, there is provided a 110

sound-deadening casing, which completely encloses the machine, except for the keyboard-extension 11 and the line-space lever 17, which protrude to the exterior thereof. 5 Said casing includes a lower member 20 and a hood or cover 21, which is swingable on a hinge 22 fast to the lower member and to the cover. The lower member is supported by a base-plate 23, upon which the feet of the 10 machine rest.

In order to facilitate the handling of a long web without necessitating the displacement of the cover, there is provided a rear table 24 mounted on a platen-frame 25 by 15 means of supporting brackets 26. Said table extends to the outside of the casing through a slot 27, which extends substantially the full width of the cover. The platen-frame 25 carries also a front table 28, 20 which is fast to a bracket 29 by means of rivets 30. Said front table carries a deflecting plate 32 fast thereto by means of rivets 33, which plate co-operates with the rear table 24 to form a throat through which a 25 work-sheet 50, which is drawn from a roll 51 at the rear of the machine, is passed and is conducted to the platen to be engaged by feed-rolls 31. The work-sheet is held in engagement with the front table by means 30 of a finger 52, and, at its uppermost end, the front table is provided with a plate 34, which plate is spaced from the plate 32 just enough to permit the free feeding of the work-sheet therebetween. Said plate 32 35 protrudes to the exterior of the casing through the slot 27. In order to prevent the emission of sound through the slot 27, there are provided slot-sealing devices, one at each side of the slot and bearing respectively on the under side of the rear table 24 and over 40 the plate 34. Said sealing devices may be made of flat rubber strips 36 enclosing a rubber tubing 37, the strips being fast to the sides of the slot by means of screws 38. It 45 will be understood that the edges 53 of the rear table 24 are curled up as shown in Figure 4, thereby providing a guard to prevent the edges 54 of the plate 34 from engaging and damaging the slot-sealing devices. 50 When, for any reason, it is desired to open the cover, the same is swung rearwardly to a position as shown in Figure 2, and, when so doing, the cover is moved away from the tables mounted on the carriage, as shown in 55 Figure 2. In order to facilitate the holding of the slot-sealing devices to the sides of the slot, there are provided plates 39 and 40, which are fastened to the cover by means of the screws 38.

60 In order to facilitate the operation of the machine, it is proposed to use an Underwood of the shiftless type, that is to say, a machine which is operated always in the same case, and has only one row of capital letter 65 types 41. Such a machine can be operated

at a much higher speed, for the reason that the operator is not distracted by the case-shifting operation. Another advantage of using such type of machine is to facilitate reading of the typed matter. 70

After typing each form, the platen is rotated by operating the line-space lever 17, and the typed form is fed to the exterior of the casing. Then the form is torn off against a knife 42, which is fast to the upper 75 edge of the slot 27 by means of the screws 38 and an intervening angular strip 43.

For the purpose of preventing the emission of sound through a slot 44 through which the line-space lever 17 protrudes, there 80 are provided slot-sealing devices 45 fast to the cover and to the casing by means of screws 46.

In order to render typing visible inside of the casing, the Underwood casing is usually 85 provided with a glass panel 47, which is fast to the cover by means of clips 48 and 49, the latter being held by means of the screws 46, which hold the upper slot-sealing device 45. 90

Variations may be resorted to within the scope of the invention, and portions of the improvements may be used without others. 95

Having thus described my invention, I claim:

1. In a combined sound-deadening casing and typewriting machine, the typewriting machine having a platen and a movable carriage, the sound-deadening casing having a slot at the rear thereof, said slot extending substantially the full width of the casing, and a chute carried by said carriage, said chute protruding through said slot to the exterior of the casing in a manner to guide a continuous work-sheet, from the exterior of the casing to the platen and then out to the exterior of the casing; so as to prevent the work-sheet from contacting with the sides of the slot. 100

2. In a combined sound-deadening casing and typewriting machine, the typewriting machine having a platen and a movable carriage, the sound-deadening casing having a slot at the rear thereof, said slot extending substantially the full width of the casing, a chute carried by said carriage, said chute protruding through said slot to the exterior of the casing in a manner to guide a continuous work-sheet, from the exterior of the casing to the platen and then out to the exterior of the casing, so as to prevent the work-sheet from contacting with the sides of the slot, and fixed slot-sealing devices for engaging said chute, said slot-sealing devices being effective to prevent the emission of sound through the slot. 115

3. In a combined sound-deadening casing and typewriting machine, the typewriting machine having a platen and a movable carriage, the sound-deadening casing having a slot at the rear thereof, said slot extending 120

substantially the full width of the casing, a chute carried by said carriage, said chute protruding through said slot to the exterior of the casing in a manner to guide a continuous work-sheet, from the exterior of the casing to the platen and then out to the exterior of the casing, so as to prevent the work-sheet from contacting with the sides of the slot, and a fixed knife arranged along-
5 side of the slot and extending substantially the full width thereof, said knife being effective for severing typed portions of the web thereagainst.

4. In a combined sound-deadening casing and typewriting machine, the latter having a platen, a movable carriage, a chute at the introductory side of the platen for conducting a web to the platen, said chute protruding to the exterior of the casing through a slot in the wall of the casing, said slot extending substantially the full width of the casing to permit the unobstructed travel of the carriage, and a guide-plate at the delivery side of the platen for guiding the typed portion of the web, said guide-plate extending to the exterior of the casing through said slot in a manner to prevent the web from contacting with the sides of the slot.

5. In a combined sound-deadening casing and typewriting machine, the latter having a platen, a movable carriage, a chute at the introductory side of the platen for conducting a web to the platen, said chute protruding to the exterior of the casing through a slot in the wall of the casing, said slot extending substantially the full width of the casing to permit the unobstructed travel of the carriage, a guide-plate at the delivery side of the platen for guiding the typed portion of the web, said guide-plate extending to the exterior of the casing through said slot in a manner to prevent the web from contacting with the sides of the slot, and means for preventing the emission of sound through said slot, said means including slot-sealing devices fast to the edges of the slot, the slot-sealing devices being resilient to permit the free movement of the carriage.

6. In a combined sound-deadening casing and typewriting machine, the latter having a platen, a movable carriage, a chute at the introductory side of the platen for conducting a web to the platen, said chute protruding to the exterior of the casing through a slot in the wall of the casing, said slot extending substantially the full width of the casing to permit the unobstructed travel of the carriage, a guide-plate at the delivery side of the platen for guiding the typed portion of the web, said guide-plate extending to the exterior of the casing through said slot in a manner to prevent the web from contacting with the sides of the slot, and means for severing the typed forms of

the web, said means including a knife having a straight-cutting edge, said knife extending substantially the full width of the casing and being secured to one side of the slot.

7. In combination, a typewriting machine and a sound-deadening casing, the typewriting machine having a revoluble platen, a traveling carriage, and a double chute for conducting a web from the exterior of the casing to the platen and from the platen to the exterior of the casing, the casing having a lower member and an upper member, the upper member having a slot extending substantially the full width thereof, through which slot the chute protrudes to the exterior of the casing, said slot being arranged in a manner to permit the unobstructed swing of the upper member in any position of the carriage.

8. In combination, a typewriting machine and a sound-deadening casing, the typewriting machine having a revoluble platen, a traveling carriage, and a double chute for conducting a web from the exterior of the casing to the platen and from the platen to the exterior of the casing, the casing having a lower member and an upper member, the upper member having a slot extending substantially the full width thereof, through which slot the chute protrudes to the exterior of the casing, and slot-sealing devices for engaging the sides of the chute in a manner to prevent the emission of sound through the slot.

9. In combination, a typewriting machine and a sound-deadening casing, the typewriting machine having a revoluble platen, a traveling carriage, and a double chute for conducting a web from the exterior of the casing to the platen and from the platen to the exterior of the casing, the casing having a lower member and an upper member, the upper member having a slot extending substantially the full width thereof, through which slot the chute protrudes to the exterior of the casing, slot-sealing devices for engaging the sides of the chute in a manner to prevent the emission of sound through the slot, and a knife, fast to the edge of the slot, for severing the typed forms.

10. In combination, a typewriting machine and a sound-deadening casing, the typewriting machine having a revoluble platen, a traveling carriage, and a double chute for conducting a web from the exterior of the casing to the platen and from the platen to the exterior of the casing, the casing having a lower member and an upper member, the upper member having a slot extending substantially the full width thereof, through which slot the chute protrudes to the exterior of the casing, said slot being arranged in a manner to permit the unobstructed swing of the upper member in any position.

of the carriage, said chute being curved at the line contacting with the edge of the slot, said curve being radial to the line of swing of the upper member, thereby permitting the free swinging of the upper member away from the chute.

11. A sound-deadening casing for a type-writing machine, the latter having a revolvable platen, a movable carriage, and means borne by said carriage for guiding a continuous work-sheet from the exterior of the casing to the platen, and from the platen to the exterior of the casing, said means including a double chute protruding through a slot in the casing to the exterior thereof, said chute being effective to prevent the work-sheet from contacting with the sides of the slot, and means for preventing the emission of sound through said slot, said last-mentioned means including flexible slot-sealing devices fast to the edges of the slot and contacting with the sides of the chute.

12. A sound-deadening casing for a type-writing machine, the latter having a revolvable platen, a movable carriage, means borne by said carriage for guiding a continuous work-sheet from the exterior of the casing to the platen, and from the platen to the exterior of the casing, said means including a double chute protruding through a slot in the casing to the exterior thereof, said chute being effective to prevent the work-sheet from contacting with the sides of the slot, and a fixed knife for severing typed portions of the work-sheet, said knife having a straight edge parallel to the slot and adjacent the delivery side thereof.

13. A sound-deadening casing for a type-writing machine, the latter having a revolu-

ble platen, a movable carriage, means borne by said carriage for guiding a continuous work-sheet from the exterior of the casing to the platen, and from the platen to the exterior of the casing, said means including a double chute protruding through a slot in the casing to the exterior thereof, said chute being effective to prevent the work-sheet from contacting with the sides of the slot, and means for preventing the emission of sound through said slot, said last-mentioned means including flexible slot-sealing devices fast to the edges of the slot and contacting with the sides of the chute.

14. A sound-deadening casing for a type-writing machine, the latter having a revolvable platen, a movable carriage, means borne by said carriage for guiding a continuous work-sheet from the exterior of the casing to the platen, and from the platen to the exterior of the casing, said means including a double chute protruding through a slot in the casing to the exterior thereof, said chute being effective to prevent the work-sheet from contacting with the sides of the slot, and means for preventing the emission of sound through said slot, said last-mentioned means including flexible slot-sealing devices fast to the edges of the slot and contacting with the sides of the chute, and means including a straight knife, fast to the upper edge of said slot, for severing the typed portions of the work-sheet.

JESSE A. B. SMITH.
